Re. 16,430

UNITED STATES PATENT OFFICE.

RALPH PULLIAN DE VAULT, OF CHICAGO, ILLINOIS, ASSIGNOR, BY MESNE ASSIGNMENTS, TO ACME MOTION PICTURE PROJECTOR COMPANY, OF CHICAGO, ILLINOIS, A CORPORATION OF ILLINOIS.

MOTION-PICTURE APPARATUS.

Original application filed May 19, 1919, Serial No. 298,013. Divided and application filed November 4, 1919, Serial No. 335,665. Original Patent No. 1,362,985, dated December 21, 1920. Application for reissue filed July 18, 1922. Serial No. 575,884.

This invention relates to improvements in motion picture apparatus.

My present application is an application for the reissue of my Patent No. 1,362,985, dated December 21, 1920, granted on my divisional application Serial No. 335,665, filed November 4, 1919, as a division of my original application, Serial No. 298,013, filed May 19, 1919.

10 The main objects of this invention are:

First, to provide in a motion picture apparatus an improved film driving and supporting means.

Second, to provide in a motion picture apparatus a means for controlling the film as it is moved intermittently, stopping it and holding it steady at the instant the driving sprocket stops, and at the same time allowing it to move freely when the sprocket 20 starts.

Third, to provide in a motion picture apparatus an improved film driving means having these advantages in which the wear on the film is minimized.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing forming a 35 part of this specification, in which:

Figure I is a side elevation of a structure embodying the features of my invention, parts being shown mainly in conventional form and parts being broken away.

40 Fig. II is a detail view mainly in vertical section on a line corresponding to line 2-2 of Fig. I.

Fig. III is a front perspective view of the aperture gate or picture framing plate.

45 Fig. IV is a longitudinal section of the aperture gate on a line corresponding to line 4-4 of Fig. III.

Fig. V is a detail view partially in section showing details of the means for supporting and driving the film.

50 Fig. VI is a detail elevation of an embodiment of my improvements as adapted to another type of moving picture machine.

Fig. VII is a view corresponding to Fig. VI, showing parts in another adjustment or 55 position.

Fig. VIII is a detail front view of the structure shown in Fig. VI and VII.

In the drawing similar reference characters refer to similar parts throughout the 60 several views, and the sectional views are taken looking in the direction of the little arrows at the ends of the section lines.

Referring to the drawing, 1 represents the frame of a moving picture machine, 2 the 65 gear box or housing for the film driving gearing and 3 the lens box. The details of the shutter are not illustrated as they form no part of this invention.

The film gate 4 has a framing aperture 5. 70 The film gate is secured at the rear of the lens box by means of set screw 6. The film casing and support are not illustrated as such parts form no part of this invention.

The film sprocket 7 is disposed at the rear 75 side of the aperture gate and is provided with teeth 8 to engage the perforations 9 of the film 10 which is of a well-known type.

The spindle 11 of the film sprocket is provided with the driven star wheel 12 coacting 80 with the "Geneva" stop driving member 13, thus providing a step by step driving means for the film. This driving means is described in detail and is the subject matter of the 85 claims of my said application for Letters Patent and is not, therefore, described in detail herein.

My improvements of this application are, however, of particular value for use in connection with such driving means as the film 90 is instantly stopped and started with the driving sprocket and held during the periods of rest.

I provide a pair of resilient belts 14 preferably formed of coiled springs. These 95 belts are supported by pulleys 15 and 16 disposed at the ends of the gate, the lower pulley 16 being disposed below the film driving sprocket 7. It will be observed that the roller 15 has its perimeter in a plane substantially tangentially with respect to the outer surface of the aperture gate, and the same 100

applies to the roller 16, so that the ends of the perimeters of said rollers are in substantially a common plane with that of the aperture gate.

6 The supports 17 and 18 for these pulleys are pivoted at 19 and 20 respectively so that they may be swung away from the film, their released position being indicated by dotted lines in Fig. I. The supports are 10 held in their released or operative position by means of the springs 29 which engage the eccentric or boss like portions 29' on the supports so that the springs engaging opposite sides of either eccentric or bosses 15 hold the supports in position.

These belts are supported by the pulleys so that their rear reaches yieldingly hold the film against the aperture gate and against the film sprocket as the film travels 20 across the same. The belts are driven by their engagement with the film sprocket so that their speed is the same as the speed of the film and so there is no surface friction of the belts on the film, and the film is fed 25 so that the wear of the sprocket therein is nominal, thus greatly increasing the life of the film.

By this arrangement of parts, the film is held so that it may be fed step by step and 30 very rapidly and at the same time is supported so that it does not flutter and is stopped instantly when the driving sprocket stops and is not injured by this rapid feed- ing.

35 In motion picture machines of this type it is customary to cut off the light during movement of the film and this interruption of the light is the cause of objectionable flicker. It is customary to provide a shutter with interrupting parts causing further interruption of the light while the film is at rest and while this reduces the pronounced flicker it also reduces the illumination upon the screen.

40 My improved film feeding means is such that the interruption can be eliminated and reduced in length thereby securing more illumination upon the screen and also better results in that the flicker is substantially 45 eliminated.

In the modification illustrated in Figs. VI, VII and VIII, I show an adaptation of my improvements to a machine of the type in which the film driving parts are adjustable to frame the picture, the aperture gate and film driving sprockets being mounted on a frame 21 supported in slides 22 for vertical adjustment. The adjustment is accomplished by means of a lever 23 which is pivoted at 24 on the main frame 1 and slotted at 25 to engage a pin 26 on the frame 21. The film sprocket 7 is mounted on this frame as is also the upper pulley 15 for the belts 14.

The lower pulley 16 is mounted on a support 27 which is pivoted at 28 on the frame 21. The spring 29 holds this support in its operative and inoperative positions, the upper end of the support being tapered to contact with the spring to secure this result. 70 Additional pulleys 30 carried by the links or rocker 31 are arranged between the reaches of the belts in the plane of the gate aperture so as to more firmly press the inner reaches of the belt at this point. The 75 resiliency of the tension of the springs of which the belts are formed accomplish this.

The upper pulley 15 is provided with a friction means to prevent over-running of the belts consisting of the spring 32 which 80 presses the friction disk 33 against the end of the pulley.

Adjustable and lock nuts 34 and 35 are provided for adjusting the tension of the spring and thereby regulating the friction. 85

I have illustrated and described my invention in these two embodiments in order to show the adaptability or application thereof. I have not attempted to illustrate or describe other modifications and adaptations which I contemplate and which might be desirable to adapt my improvements to certain types of machines as I believe the disclosure made will enable those skilled in the art to which my invention relates to 95 embody or adapt the same as may be desired.

Having thus described my invention, what I claim as new and desire to secure by Letters Patent is:

100

1. In a motion picture apparatus of the class described, comprising an intermittently driven film, the combination of an aperture gate, a driving means for said film comprising a film sprocket disposed at the lower end of the gate, a pair of belts formed of coiled springs, pulleys for said belts disposed at the ends of said gate, the lower pulleys being disposed below said film sprocket so that the rear reaches of said 105 belts yieldingly hold the film against the gate and the film sprocket as it travels over the same, said belts being driven by said film sprocket.

2. In a motion picture apparatus of the class described, comprising an intermittently driven film, the combination of an aperture gate, a driving means for said film comprising a film sprocket disposed at the lower end of the gate, a pair of belts 110 formed of coiled springs, pulleys for said belts disposed at the ends of said gate, the lower pulleys being disposed below said film sprocket so that the rear reaches of said 115 belts yieldingly hold the film against the gate and the film sprocket as it travels over the same, said belts being driven by said film sprocket, pivoted supports for said 120

125

130

135

pulleys, and springs for holding said supports in their operative positions.

3. In a motion picture apparatus of the class described, comprising an intermittent-
ly driven film, the combination of an aperture gate, a driving means for said film comprising a film sprocket, a pair of belts formed of coiled springs, pulleys for said belts disposed to yieldingly hold the film 10 against the gate and the film sprocket as it travels over the same, said belts being driven by said film sprocket, pivoted supports for said pulleys, and springs for holding said supports in their operative positions.

4. In a motion picture apparatus of the class described, comprising an intermittent-
ly driven film, the combination of an aperture gate, a driving means for said film 20 comprising a film sprocket, a pair of belts formed of coiled springs, pulleys for said belts disposed to yieldingly hold the film against the gate and the film sprocket as it travels over the same.

5. In a motion picture apparatus of the class described, comprising an intermittently driven film, the combination of an aperture gate, a driving means for said film comprising a film sprocket disposed at the lower 30 end of the gate, a resilient belt, pulleys for said belt disposed so that the belt engages the film as it travels across the gate and over the film sprocket, pivoted supports for said pulleys, and springs for holding said supports in their operative positions.

6. In a motion picture apparatus of the class described, comprising an intermittent-
ly driven film, the combination of an aperture gate, a driving means for said film comprising a film sprocket, a resilient belt, pulleys for said belt disposed so that the belt engages the film as it travels across the gate and over the film sprocket, said 45 belt being driven by said film sprocket.

7. In a device of the character described, in combination, a film engaging and moving sprocket, an aperture gate on one side of the sprocket, a roller on the other side of the 50 sprocket, and a feeding belt passing around said roller and before the aperture gate.

8. In a device of the character described, in combination, a film engaging and moving sprocket, an aperture gate on one side of the sprocket, a roller on the other side of the 55 sprocket, and a feeding belt passing around said roller and before the aperture gate, said sprocket and belt being driven at the same linear speed.

9. In a device of the character described, in combination, a film engaging and moving sprocket, an aperture gate on one side of the sprocket, a roller on the other side of the 60 sprocket, and a feeding belt passing around said roller and before the aperture

gate, and means for holding said belt against the sprocket.

10. In a device of the character described, in combination, a film moving sprocket, an aperture gate on one side of the sprocket, 70 and a feeding belt engaging the sprocket at the side opposite to the aperture gate and said belt passing around the sprocket and before the aperture gate.

11. In a device of the character described, in combination, an aperture gate, a roller on one side of the gate, a film sprocket on the other side of the gate, said roller and sprocket being disposed on opposite ends of the gate, with the adjacent extreme ends 75 of their perimeter substantially in a common plane with the aperture gate, a second feed roller on the side of the sprocket opposite to that on which the aperture gate is located, and a feeding belt passing around 80 said two rollers.

12. In a motion picture apparatus of the class described, in combination, an aperture gate, film driving and guiding means comprising a sprocket and a movable belt disposed so that the belt engages the film as it travels across the gate and over the film sprocket and retains the film in position 85 against the sprocket and before the aperture gate.

13. In a motion picture apparatus of the class described, in combination, an aperture gate, film driving and guiding means comprising a sprocket and a movable belt disposed so that the belt engages the film as it travels across the gate and over the film sprocket and retains the film in position 90 against the sprocket and before the aperture gate, said belt being driven synchronously with said film sprocket.

14. In a motion picture apparatus of the class described, in combination, an aperture gate, film driving and guiding means comprising a sprocket and a movable belt disposed so that the belt engages the film as it travels across the gate and over the film sprocket and retains the film in position 95 against the sprocket and before the aperture gate, said belt being driven by said film.

15. In a motion picture apparatus of the class described, in combination, an aperture gate, driving means for said film comprising a film sprocket, a belt, pulleys for said belt one of said pulleys being adjacent and to the rear of said sprocket so that the belt engages 110 the film as it travels across the gate and over the sprocket, said pulleys being yieldably supported in their operative positions.

16. In a motion picture apparatus of the class described, in combination, an aperture 115 gate, driving means for said film comprising a film sprocket, a resilient belt, pulleys for said belt one of said pulleys being adjacent and to the rear of said sprocket so that the belt engages the film as it travels across 120

125

the gate and over the sprocket, said pulleys being yieldably supported in their operative positions.

17. In a moving picture machine, the combination of a member having an opening therein through which the beam of light is projected, means for moving a film intermittently and a yieldingly resistantly expansible moving guiding device for the film, movable with the film in the direction of the length thereof by engagement with said moving means, said guiding devices being driven synchronously with the film.

18. In a moving picture machine, the combination of a member having an opening therein through which a beam of light is projected, means for moving a film intermittently, and a moving yieldingly resistantly expansible guiding means arranged and constructed for guiding the film past the opening and into contact with the film moving means.

19. In a motion picture machine, the combination of a member having an opening therein through which the beam of light is projected, means for moving a film intermittently and a moving film guiding means engaging said film moving means and formed of coiled spring material.

20. In a moving picture machine, the combination of a member having an opening therein through which the beam of light is projected, means for moving a film intermittently and a belt engaging said film moving means and formed of coiled spring material for guiding the film.

21. In a moving picture machine, the combination of a member having an opening therein through which the beam of light is projected, means for moving a film across the opening, and means for guiding said film

past said opening and into contact with said film moving means.

22. In a moving picture machine, the combination of a member having an opening therein through which the beam of light is projected, means for moving a film intermittently, and means movable synchronously with the film moving means for moving and guiding said film past said opening and into contact with said film moving means.

23. In a motion picture apparatus of the class described, in combination, an aperture gate, film driving and guiding means comprising a sprocket and a belt, means for supporting the belt upon said gate and said sprocket so that it engages the film as the latter travels across the gate and over the film sprocket.

24. In a motion picture apparatus of the character described, in combination, an aperture gate, a sprocket at one end of the gate for driving the film strip, and a belt for guiding the film strip along said gate and into operative engagement with said driving sprocket.

25. In a motion picture apparatus of the character described, in combination, an aperture gate, a sprocket at one end of the gate for driving the film strip, and a resilient belt for guiding the film strip along said gate and into operative engagement with said driving sprocket.

26. In a motion picture apparatus of the character described, in combination, an aperture gate having a curved face, a sprocket at one end of the gate for driving the film strip, and a belt for guiding the film strip along the curved face of said gate and into operative engagement with said driving sprocket.

RALPH PULLIAN DE VAULT.
